UNITED STATES PATENT OFFICE.

EUGENE LA SARGE, OF LUDINGTON, MICHIGAN.

RAILROAD-SWITCH.

1,179,535.

Specification of Letters Patent. Patented Apr. 18, 1916.

Application filed July 2, 1913. Serial No. 776,921.

To all whom it may concern:

Be it known that I, EUGENE LA SARGE, a citizen of the United States, and a resident of the city of Ludington, in the county of 5 Mason and State of Michigan, have invented certain new and useful Improvements in Railroad-Switches; and I do hereby declare that the following is a full, clear, and exact 10 description of the same, reference being had to the accompanying drawings, and to the numerals of reference marked thereon, which form a part of this specification.

A great many types of switches have been constructed with various objects in view, but 15 in a great many cases it has been found that weather conditions present a problem which in a large measure determine the practicability of the device. Switches of simple construction such as a type of the well known 20 point switch have proved most successful where weather conditions permit for the reason that switches so constructed are easy to manipulate, whereas switches designed to be unaffected by climatic conditions have been 25 so complicated and expensive of installation and upkeep as to practically preclude the use thereof. One of the most favored types 30 of switches is that switch known as the point switch, but due to its simplicity it has been found to be easily affected by snow and ice, thus preventing operation thereof, although 35 the switch is practically unaffected in its operation by changes of temperature.

This invention relates to an improved type 40 of point switch which is self-cleaning in its operation to obviate trouble in operation due to the caking of snow or ice in and around the parts thereof, inasmuch as the parts are so constructed as to readily clear and free 45 themselves when the switch is thrown.

It is an object of this invention to construct a point switch wherein the point rails are pivotally mounted to swing about a substantially horizontal axis whereby the point 50 rails are actually rotated through a small arc to swing the rails into proper position, by such movement serving to sweep foreign matter from between the same to prevent jamming thereof.

It is also an object of this invention to provide an improved type of point switch wherein the point rails are securely linked to one another to insure proper simultaneous

movement thereof, such connection permitting a pivotal movement of each of said 55 rails.

It is also an object of this invention to provide rotatably and eccentrically mounted point rails, and curved slide plates adapted to support said point rails at a plurality of 60 points.

It is also an object of this invention to provide revoluble point rails supported by curved slide plates, and means associated with said rails to maintain the same in close 65 bearing engagement with said slide plates at all times.

It is also an object of this invention to provide together with rotatable point rails and actuating mechanism therefor, reinforcing members adapted to swing into engagement therewith when the respective point rails are in switching position.

It is also an object of this invention to provide point rails rotatable about a longitudinally directed axis and curved supporting slide plates therefor conforming to the sweep of said rails to insure proper positioning of the same at all times.

It is also an object of this invention to provide point rails and slide plates, the latter slotted to receive engaging means attached to the point rails to maintain said point rails in contact with said plate at all 80 times.

It is also an object of this invention to provide engaging means between the point rails and slide plates wherein the base of the rail serves in all positions to cover and protect the engaging means between the same 90 and said slide plates.

It is also an object of this invention to provide point rails suitably connected to one another to insure concurrent movement thereof, and reinforcing means adapted to 95 be respectively thrown into and out of operating position by mechanism linked to the connection between said rails.

It is also an object of this invention to provide point rails which are suitably 100 mounted upon a pivot extending into the head of the rail, whereby the rail points swing into position through an arc, guided by suitably curved slide plates, serving by such movement to sweep the intervening 105 space between the main rails and the point

rails to clear the same of any foreign matter and prevent jamming of the rails.

It is also an object of this invention to provide a switch, wherein the point rails are elevated as they swing into position, thus sweeping any foreign matter lying between the rails upwardly and away therefrom.

It is furthermore an object of this invention to provide a simple point switch with 10 rotatably mounted point rails and means for actuating the same into position and suitably supporting and guiding the same into such positions at all times.

It is finally an object of this invention to 15 provide a device consisting of only a few parts easy of manufacture and assembly, and serving to clear the switch of foreign matter with each actuation thereof.

The invention (in a preferred form) is 20 hereinafter more fully described in the accompanying drawings and specification.

In the drawings: Figure 1 is a top plan view of a section of track showing the point rails of a point switch embodying my invention connected thereto. Fig. 2 is a side elevation thereof. Fig. 3 is a section taken on line 3—3 of Fig. 1. Fig. 4 is a section taken on line 4—4 of Fig. 1. Fig. 5 is a section taken on line 5—5 of Fig. 1. Fig. 6 is a 25 fragmentary top plan view illustrating the reinforcing means for the point rails. Fig. 7 is a fragmentary top plan view illustrating the actuating mechanism for the reinforcing means for the point rails. Fig. 8 is a fragmentary detail partly in elevation and partly in section illustrating the pivotal connection between a point rail and a main rail. Fig. 9 is a detail illustrating the connection between a point rail and a slide plate taken on line 30 9—9 of Fig. 3, and with the point rail in switching position. Fig. 10 is a section taken on line 10—10 of Fig. 9. Fig. 11 is a section taken on line 11—11 of Fig. 3. Fig. 12 is a section taken on line 12—12 of Fig. 45 5 with parts omitted.

As shown in the drawings: Referring to the drawings it will be seen that the device is mounted as usual upon ties 1, the reference numerals 2 and 3, denoting respectively the main track rails.

Rails numbered 4 and 5, respectively, denote the turnout rails and the rails numbered 6, and 7, denote the point rails, of the switch. The switch, as shown in Fig. 1, is set in closed position or that permitting thoroughfare on the main track. Any number of slide plates 8, desired are spiked to the ties the upper surface of said slide plates being curved to receive thereon the under 55 curved surface of the base of the point rails. Said slide plates are also bolted to the respective rails 3, and 4, by means of bolts 9, and a T-shaped slot 10, is provided in said upper curved surface. The base portion of each 60 of said point rails is tapped to receive a bolt

11, therein at a position to register and engage said slot 10, said bolts serving to guide the point rails in their movement and also positively retain the same upon said slide plates.

As is usual in point switches the point rails are rolled down to a taper at the rail engaging extremities and inasmuch as in my invention the base of said rail must be curved the rail has a continually varying 75 cross-section, as illustrated more clearly in Figs. 3, 4, and 5. That portion of the point rail near the pivot connection to the main rail is practically of standard cross-section except for the rounded under surface of the 80 base, as shown in Fig. 5. However, a section taken within the length that has been rolled to a taper discloses the base portion and the flange of the rail as merging into one, and of course with a narrowed head 85 portion.

At the extreme end of the point rails which are adapted to contact the main turnout rails respectively, the point rails are shown as consisting of a single curved portion of metal, the flange, the head, and the base of rails having been merged into the one curved form adapted to slide upon the respective slide plates. Lugs 12, are provided on said point rails, and pivotally 90 linked thereon are the tie rods 13, which constrain said point rails to move simultaneously, and yet permit a relative pivotal movement therebetween. An actuating rod 12^a, is slotted at its ends and engages pins 100 extending through certain of the lugs 12, thus permitting a certain amount of lost motion to take place before the point rails are shifted by mechanism hereinafter described. For the purpose of throwing said 105 point rails into switching position any type of switch stand 14, is mounted at one side of the track, and a connecting rod 15, serves to transmit the throw from the switch stand to a bar 16, connected to the actuating rod 110 12^a, of the point rails. Inasmuch as the curved slide plates do not present a reaction surface normal to the weight applied upon the point rails, means are provided for suitably bracing said point rails at the 115 base thereof, to prevent the same riding down upon the curved incline when a weight is applied thereon. This means consists of bell cranks pivoted to one or more of the slide plates 8 comprising an arm 17, and 120 a reinforcing wedge 18, rigidly connected thereto, so that as said arm 17, is moved in one direction, the wedge 18, will be thrust into a position behind one edge of the base of the point rail to prevent reverse 125 rotation or movement thereof, and when said arm 17, is moved into its other position said wedge 18, will be retracted, thus permitting a retrograde movement of said rails. For the purpose of actuating said reinforce- 130

ing crank as the rail is moved into switching position, the arm 17, thereof is linked to another bell crank by means of a connecting rod 19, the other of said bell cranks being pivoted adjacent the actuating rod 12^a, and having an arm 20, engaging a pin in said rod 12^a, and with another actuating arm 21, pivotally connected to said connecting rod 19. Thus as the point rails are switched from one position to another with the consequent transverse movement of the tie rods, the arms 17 and 21, through the intermediation of the connecting rod 19, serve to first actuate the crank wedges 18, either into reinforcing position or release position, as the case may be, the respective mechanism being mounted one for each point rail such that as one moves into locking position the other moves into release or unlocking position and secondly, the point rails. The pivotal connection between the point rails and the main track and turnout rails comprises a pin 22, threaded into the point rail and engaging in a suitable aperture in the respective abutting rail to which it is connected. Said pin is mounted slightly to one side of the center of said point rail so that rotation of said rail about said pivot point will cause the tapered extremities thereof not only to rotate about an axis, substantially longitudinal of the rails, but also cause the same to move through an arc as disclosed in Figs. 3, 4, and 5, to move said point rails when not in switching position clear of the main track rail. Of course, the angle of rotation for the entire length of the point rails is the same throughout, but due to the eccentric mounting thereof the amplitude of such movement varies from a minimum at the pivot point to a maximum at the tapered extremity of said rail. Consequently, the slide plates arranged at different points beneath the point rails are each of slightly different construction, the length of curvature thereon and radius of curvature being dependent upon the distance thereof from the pivot point of the point rail.

The operation is as follows: Regardless of whether the switch is in open or closed position, one of the point rails is always in operating position. As shown in Fig. 1, the switch is in closed position, and the cars may pass over the switch on the main track line. In this case the point rail 6, forms a part of the main track line. When the switch is in open position the point rail 6 is rotated, simultaneously with the point rail 7, such movement serving to move the point rail 6, out of contact with the stock rail 5, and moving the point rail 7, into contact with the main rail 3, in which position the cars will be diverted to a side track. Usually in point switches, snow or ice becomes wedged between the fixed rails and the movable

point rail, thus preventing a closing of the point against the fixed rail, but, as more clearly illustrated in Fig. 10, of my device it will be seen that the point rail does not swing into an abutting position against the fixed rail, but rather sweeps upwardly thereagainst, and inasmuch as the fixed rail is flat on its inner surface with the slide plates supporting the point rail, such sweeping movement of the point rail into position serves to clear the same of any foreign matter that may have become lodged therebetween to prevent proper manipulation of the rail.

Of course, I have shown merely one type of construction whereby a rotational rail is adapted to a switch to insure proper operation thereof, at all times, and obviously the particular details of construction may be varied through a wide range without departing from the principles of my invention. I therefore do not purpose limiting the patent granted otherwise than necessitated by the prior art.

I claim as my invention:

1. In a device of the class described, a point switch comprising point rails, pivots connecting said point rails at one end only with fixed rails to permit a rotational bodily lateral shift of the free ends of said point rails, and curved guide slide plates for said free ends to insure the proper movement thereof.

2. In a device of the class described, point rails, curved slide plates supporting the same, and means connecting said point rails with said slide plates to maintain the point rails in engagement therewith at all times.

3. In a railway switch, fixed rails, point rails pivotally connected thereto at one end only and to each other and adapted at their free ends to rotate about a substantially horizontal axis, and means guiding and retaining said free ends in the proper path of movement.

4. In a device of the class described, a fixed rail, point rails pivotally connected thereto, curved slide plates supporting said point rails, bolts in said point rails engaging in slots in said slide plates to retain the point rails thereon and guide the same in a proper path, means rotating said point rails into proper position, and reinforcing wedges adapted to swing into abutment with the base of said point rails when in switching position.

5. In a device of the class described, point rails, an actuating rod linked to each thereof, wedge bell cranks adapted to engage against the base of said point rails to reinforce the same, bell cranks mounted adjacent said actuating rods and connected thereto to be actuated thereby, and connecting rods connecting said bell cranks to each other to insure proper movement of

said wedge cranks with movement of the tie rods.

6. In a device of the class described, point rails, a curved under face thereon, curved slide plates supporting said point rails, and means connected to said point rails and engaging said slide plates to maintain and guide the point rails thereon.

Copies of this patent may be obtained for five cents each, by addressing the "Commissioner of Patents, Washington, D. C."

In testimony whereof I have hereunto subscribed my name in the presence of two subscribing witnesses.

EUGENE LA SARGE.
